F. HASTRICH

FLUSHING CISTERN

Filed Oct. 22, 1923

UNITED STATES PATENT OFFICE.

FERDINAND HASTRICH, OF CAMPERDOWN, NEAR SYDNEY, NEW SOUTH WALES,
AUSTRALIA.

FLUSHING CISTERNS.

Application filed October 22, 1923. Serial No. 670,147.

To all whom it may concern:

Be it known that I, FERDINAND HASTRICH, subject of the King of Great Britain, residing at 140 Parramatta Road, Camperdown, near Sydney, New South Wales, Australia, have invented new and useful Improvements in Flushing Cisterns, of which the following is a specification.

This invention relates to semi-automatic flushing cisterns of the type ordinarily used in connection with sanitary basins.

In flushing cisterns according to the present invention, a float is carried on a trip lever which is fulcrumed on a counter-weighted pull lever, which is in turn fulcrumed intermediate its ends on a fixed bracket. The trip lever is armed with a latch finger which is engageable with a staple lug on the fixed bracket, and its movement about its fulcrum is limited by stops which at either extreme of its permitted range of movement engage the counterweighted pull lever. The pull lever is fitted with a cam which controls the service valve through which the cistern is charged with water.

Normally the cistern is empty. When the pull lever is thrown by chain pull, its outer end is raised and the latch on the trip lever is thereby lifted to and engaged with the staple lug. In this movement the flush valve, which is pendent from the pull lever, is dropped onto its seat, and the service valve is opened by the cam; and the pull lever is held by the latch of the trip lever until released by another action. Water now flows into the cistern. When normal charge level is reached the float is lifted by the water, with the result that the latch is disengaged from the staple and the pull lever is no longer held. The counterweight then operates to reverse the pull lever, and in this reversing movement the flush valve is lifted and the service valve is permitted to close.

In the accompanying drawings:—

Fig. 1 is a sectional elevational view of a cistern according to the present invention;

Fig. 2 is a vertical cross section on the plane 2—2 Fig. 1; and

Fig. 3 is a fragmentary sectional view showing an alternative method of mounting the cistern chamber on the carrier bracket.

The cistern chamber 10 is supported on a metal bracket 11 which is adapted to be spiked to a wall. The bottom ends of this bracket are upturned as shown at 12 and carry bearers 13. The two bearers 13, one 60 on either leg of the frame 11, together form a cradle to carry the cistern chamber 10. This chamber is preferably constructed of earthenware or concrete, but may be of sheet metal. It is formed with locating 65 flanges 14 which set on either side of the bearers 13, or alternatively is grooved as shown at 15 (Fig. 3) across the bottom to receive the bearers 13.

The chamber 10 is fitted with a flush valve 70 comprising a throat seating 16 secured in any desired manner in an aperture formed in the bottom of a sump cavity 17 to connect the cistern to the flush pipe 18. 19 is a drop valve with guide fingers arranged 75 for bringing it to centre in the seating piece 16.

20 is a chain or flexible wire by which the flush valve 19 is connected to the pull end of the pull lever 21. 22 is the pull 80 chain. 23 is a counterweight on the back end of the pull lever 21. 24 is a cam shaped lug secured to the lever 21, and 25 is a fulcrum pin passing through the cam lug 24 and through the lugs 26 which depend 85 from either side of the water service valve housing 27. 28 is a bracket on the housing 27, and 29 a staple lug offset on the end of said bracket. 30 is the charging pipe which is in connection with the cas- 90 ing 27. 31 is a screwed-on collar connection into which the top end of the valve cas- 95 ing 27 is screwed, 32 being the service pipe which is screwed into the top end of the collar 31. The collar 31 is mounted by a bracket 33 on the wall frame 11. The whole of the mechanical fitting is therefore quite independent of the cistern chamber mounting.

A trip lever 35 is pivotally mounted at 100 36 on the outer end of the pull lever 21. 37 is a bell or other form of float, preferably a hemispherical float as shown. The back end of the trip lever 35 is armed with a latch 37 which in the pulled position of the 105 lever 21, the cistern being empty, is engageable with the staple 29 on the bracket 28. The nosing of the latch 37 is such that in the rising movement it trips readily over the staple 29 and engages with its top face. 110

38 and 39 are stops on the arm 35 engageable respectively with the underside and the top side of the lever 21 to limit the range of movement of the trip lever 35 on 5 the pin 36 relatively to the pull lever 21. In idle position the counterweight 23 is down and the float 37 hangs below water level in the cistern chamber 10, and the latch 37 is not engaged with the staple 29. 10 In this position the cam 24 holds the service valve contained in the casing 27 closed, so that water does not enter the cistern through the feed pipe 30. During this time the flush valve 19 is open. When the pull 15 chain 22 is operated, the lever 21 is tipped until the latch 37 is engaged with the staple 29, as shown in Fig. 1. In this lifting movement the flush valve 19 is dropped on to its seat, and the service valve in the casing 27 is allowed to open consequent on the release movement of the cam 24. The cistern then begins to fill. As it fills the water acting on the float 37 ultimately causes it, when the appropriate level has 20 been reached, to tip the trip lever 35 and release the latch 37 from the staple 29. Thereupon the counterweight 23 acts to drop the lever 21 till it contacts with the stop 39 on the trip lever 35. It is, however, prevented by the buoyancy of the float 37 from falling sufficiently far to cause the cam 24 to fully close the service valve 25 in the housing 29. When the lever 21 drops it pulls on the chain 20 and lifts the flush 30 valve 19. The flush then discharges in the usual way through the fully opened valve 19 and the pipe 18, and the water level in the cistern thus falling allows the float 37 and the lever 21 to come to the low position 35 and completely close the service valve in the housing 29. This gradual closing of the service valve eliminates "water hammer" effect which is found when the service valve is closed suddenly. Owing to the op-

eration of the cam device for slowly closing 45 the service valve, that valve may be made much larger in diameter than is usual with inlet valves which are operated directly by the lever movements, with the result that noise in charging the cistern is minimized. 50 The parts remain in the position to which they have thus come until the chain is again pulled.

What I claim as my invention and desire to secure by Letters Patent is:—

1. In a flushing cistern, a service valve, a flush release valve, a pull lever, a cam-shaped lug carried by said lever and pivotally mounted on and adapted to operate said service valve, an operating member carried by one end of said lever, means connecting said end of the lever with the flush release valve, a counterweight carried by the opposite end of said lever, a trip lever pivoted directly to said pull lever, a stationary lug, a latch carried by one end of the trip lever engageable with the stationary lug to maintain the second mentioned end of the pull lever in elevated position, and a float carried by the opposite end of the trip lever adapted, when the water in the cistern attains a predetermined level, to swing said trip lever relative to the pull lever whereby to disengage the latch from the lug and permit the second mentioned end of the pull lever to descend.

2. A flushing cistern as claimed in claim 1 characterized by the provision of stop members on the trip lever coacting with the pull lever whereby to limit the relative swinging movement of the levers and prevent the pull lever from falling to its lowermost position coincident with the disengagement of the latch from the lug.

In testimony whereof I have signed my name to this specification.

FERDINAND HASTRICH.
